UNITED STATES PATENT OFFICE.

CHARLES FRANCIS JENKINS, OF WASHINGTON, DISTRICT OF COLUMBIA.

ELECTRIC METER.

1,364,377.

Specification of Letters Patent.

Patented Jan. 4, 1921.

Application filed June 22, 1918. Serial No. 241,386.

To all whom it may concern:

Be it known that I, CHARLES FRANCIS JENKINS, a citizen of the United States, and resident of Washington, in the District of Columbia, have invented certain new and useful Improvements in Electric Meters, of which the following is a specification, reference being had therein to the accompanying drawing.

10 This invention relates to indicating the heating effect of an electric current and thus approximately showing the strength of the current itself.

15 The principal objects are to provide an extremely inexpensive, simple and durable meter without articulating parts, and one that will last indefinitely, even with rough use by careless or uninstructed users.

20 With these objects in view, an expansion bar, made in a well known way of two metals united face to face and differing in expansion when temperature rises, is longitudinally divided, except near one free end, and has the two parts or arms fixed, respectively, to the terminals of a circuit the current in which is to be measured, the deflection of the bar indicating the current passing through it.

25 In the accompanying drawings, 30 Figure 1 is a face view of the thermostat. Fig. 2 is a view looking in the direction of the arrow of Fig. 1, the casing being in section.

35 Fig. 3 is a plan view of an expansion strip. Fig. 4 is a cross section of the same strip. Fig. 5 is a plan view of the same strip after it is sawed longitudinally along its medial line.

40 In these figures, A represents a meter casing, B an insulating plate fixed to the bottom of the casing, C, D binding posts secured to the plate B, extending outward through the bottom of the casing and inwardly from the plate, their free ends carrying, respectively, the ends E, E', of an expansion bar F, made up of metals having different coefficients of expansion, *e. g.* brass and steel. This bar is divided along its medial longitudinal axis to form parts or arms 45 E, E' in a plane and slightly separated except at one end where they are connected integrally by an uncut end portion G of the bar. The bar thus divided is bent to the form shown in Fig. 1, forming two long double arms J, K connected near the middle of the bar by a nearly complete loop L of cy-

lindrical form. The arm J has the ends of its parts bent oppositely outward in planes determined by it and the corresponding part of the arm K. These outwardly turned ends M, N, are fixed, respectively, to binding posts C, D, already mentioned, which pass through the bottom of the casing, without making electrical contact therewith, and receive, respectively the terminal O, O' of a 60 circuit the current in which is to be indicated. The free end of the double arm K will obviously swing when the expansion bar as a whole is heated and this movement will be aided and increased in amplitude by the 65 flexing of the arm J and the loop L, and thus a slight change in temperature will give a wide indicating movement of this free end of the arm K.

70 Preferably the casing is provided with a 75 protecting glass plate P and between this plate and the expansion bar is an opaque disk Q having a graduated arc alongside a curved opening R through which the free end of the arm K is visible and along which 80 it travels.

85 The apparatus has no articulated parts and nothing moves except the free part of the expansion bar which automatically bends and at the same time serves as a pointer or index finger sweeping along the graduated arc. With such construction, neither time nor any ordinary use can impair the usefulness of the meter.

90 What I claim is:

1. The combination with two parallel slightly separated arms connected at one end and having the opposite ends fixed and in electrical connection with the terminals, respectively, of a circuit the current in 95 which is to be indicated, said arms having on opposite faces metals differing in expansion under increase in temperature, whereby the ends of the arms which are connected together pass from normal position through a 100 distance commensurate with the heating and the current which heats.

2. A compensation bar divided from one end nearly to the opposite end and as a 105 whole bent centrally to form a loop in the plane of the parts between which it lies, the separated ends being adapted for connection with the terminals of an electric circuit and fixed in position while the parts upon the opposite side of the loop are free to swing as 110 a pointer when the heating effect of the current varies.

3. In an electric meter, a thermostatic two-metal strip bent near its middle to form an approximately cylindrical loop in the plane of the other parts, the strip being split 5 from one end nearly to the opposite end and the branches so formed having their free ends fixed and adapted to be electrically connected, respectively, to the terminals of a circuit in which the current is to be measured, while the free end of the strip as a 10 whole is free to swing as the heating effect of the current varies.
4. The combination with a case having within two fixed electric terminals, of a compensation bar having two slightly separated 15 branches continuous at one end and at their opposite ends fixed to said terminals, respectively, while the bar is otherwise free and provided with a central loop whereby it may swing through a wide arc as the current 20 varies.

In testimony whereof I hereunto affix my signature.

CHARLES FRANCIS JENKINS.
